UNITED STATES PATENT OFFICE.

ISIDOR KITSEE, OF PHILADELPHIA, PENNSYLVANIA.

MULTICOLOR SCREEN FOR PHOTOGRAPHY.

Application filed December 31, 1918. Serial No. 269,059.

To all whom it may concern:

Be it known that I, ISIDOR KITSEE, a citizen of the United States, residing at Philadelphia, in the county of Philadelphia and 5 State of Pennsylvania, have invented certain new and useful Improvements in Multicolor Screens for Photography, of which the following is a specification.

My invention relates to an improvement 10 in color screens for photography.

Its object is to produce a color screen integral with a photographic blank.

In the accompanying drawing I have illustrated the different steps for producing a 15 multi-colored screen on a moving picture film, but it is obvious that this my invention may also be used for still pictures.

In the accompanying drawing the Figs. 1 to 7 inclusive are plan views, illustrating 20 part of a moving picture film in the process of preparing the same with a color screen.

I will now describe the mode or method of procedure in obtaining the required result, and in doing so I will refer to the different 25 numbers as indicating the different parts of these figures, and I will here describe this my invention as being applied to moving picture films.

Moving picture films are today produced 30 of dissolved cellulose, such for instance as is known in commerce as "celluloid."

In Fig. 1 this film or rather part of same is indicated by 1, and the perforations with which these films are usually provided by 35 1^a, as the first step in producing the color screen I provide the surface of film 1 with a gelatine, preferably chromated and indicated in Fig. 1 by 2. The film which is now sensitized with this chromated gelatine, is 40 subjected to the action of light under a pattern, consisting of a transparent base and opaque lines laterally drawn across the face of the pattern. It is well understood by persons versed in the art, that if a blank or film sensitized with chromated gelatine 45 is subjected to the action of rays of light in conjunction with a pattern, consisting in part of transparent and in part of opaque material those parts of the blank or film coinciding with the transparent part of the pattern, during the time that the blank or film is subjected to the rays of light, undergo a chemical change whereby the gelatine so acted upon by the light is made to a 50 great extent insoluble in tepid water, whereas those parts of the blank or film, coincid-

ing with the opaque part of the pattern, during the time that this blank or film is subjected to the rays of light, will remain unaffected by said rays and are therefore readily 60 removed by tepid water. When therefore a film, such as is illustrated in Fig. 1, is subjected through a transparent pattern with suitable laterally drawn lines of opaque material to the rays of light, and then subjected 65 to the washing out process, the surface of the film will consist of lateral lines of gelatine, alternating with lines of exposed celluloid, as is clearly indicated in Fig. 2 in which 3 indicates the lines of gelatine, and 70 4 indicates the lines or space washed free from the gelatine and in which therefore the celluloid is exposed. The gelatine lines are then tinted with the required dye, and it is supposed that the dye is a suitable 75 green, soluble in water. The film will therefore present an appearance substantially as is indicated in Fig. 3 in which 5 represents the tinted gelatine.

The next step is, to tint or color the exposed celluloid. I have discovered, that certain dyes soluble in strong alcohol, are also soluble in acetone, which, fortunately is also a part solvent of the celluloid out of which the film proper consists. In practise I have 80 found it necessary to decrease the dissolving properties of the acetone on the celluloid, as otherwise even a few seconds' exposure of the bare celluloid to the acetone-dye, will 85 gerately injure the film and make the same 90 useless for my purpose. The material to decrease the reaction, has to be of such a nature as not to affect the dyed gelatine and if possible even to add to the repelling property of the acetone. After prolonged experiments I have found that carbon tetrachlorid 95 is very well adapted for this purpose. It is true, that to some extent formaldehyde may be substituted for carbon tetrachlorid, but yet I have found the action of carbon tetrachlorid far more practical than that of formaldehyde. Different colors may be used, but I have here shown the celluloid as being colored with a suitable red, and Fig. 4 indicates substantially the appearance of the film 100 after this step, and in this figure, 5 indicates the colored gelatine, and I use the number 6 to indicate the now colored celluloid. It has to be stated that the dye solution in its entirety is repelled by the gelatine and the 105 gelatine therefore will not take up the color of this solution and will remain absolutely 110

unaffected by same. After the completion of the coloring process of the celluloid, the whole surface of the film is provided with a layer of varnish. It is preferred and in reality required that this varnish should not be affected by the later process of dyeing or coloring one or the other parts of the film. In Fig. 5, 10 clearly indicates the coating of varnish, partly broken away so as to show the underlying colors.

The next step is, to expose the celluloid of the film proper longitudinally at different places, that is to free the underlying celluloid from the gelatine and varnish in longitudinal lines properly spaced from each other. This proceeding may easily be accomplished with the aid of a device, provided with a series of properly sharpened points or cutting edges, Fig. 6 illustrates these lines and in this figure these lines are indicated by 7; illustrating the continuous lines of the exposed celluloid. It has to be stated, that in clearing or cutting away the colored gelatine overlying the celluloid film, the colored lines 6 of the celluloid proper will not be injuriously affected, if the cutting is not deep enough to cut the film itself; for the reason that the special dye above described, to tint the exposed celluloid, impregnates the same to a comparatively great depth:—For this reason the empty or uncolored spaces of the lines 7, alternate with the colored spaces of the celluloid. These exposed lines of celluloid are then impregnated with any of the required colors here shown as consisting of a blue dye and these lines, properly dyed in the blue color are indicated in Fig. 7 by the numeral 8. The whole surface of the film therefore consists of a series of figures, here squares, the square of one color alternating with the square of a second color.

I have illustrated and described a process with the aid of which three colors may be applied to the surface of a suitable blank or film, without in the least producing undue interference between one color and the other color. But in reality, the screen presents not only the three colors applied to the

film but it represents a fourth color, being the effect of the combined two colors red and blue at the intersection of the lateral red and longitudinal blue lines; and if these two colors are proper in relation or balance as to each other, they will produce a violet or blue violet, fortunately just the color required in all color screens and not present in any of them. These junctions of the two colors, of the red (6) of the lines 4, and the blue (8) of the lines 7, producing as they do the violet color, are indicated by 9.

The screen therefore comprises, the four colors red, green, blue and violet, embracing in their combinations the whole spectrum.

Having now described my invention, what I claim as new and desire to secure by Letters Patent is:—

1. In the production of multi-colored screens for moving picture films the steps as follows:—Surfacing a celluloid film with bichromated gelatine, producing from said gelatine, with the aid of light rays, configurations on the surface of said film, tinting said configurations with one color, impregnating then the exposed celluloid with a second color, covering the surface of the gelatine and exposed celluloid with a varnish, removing part of the varnish and gelatine and impregnating the so exposed part of the celluloid with a third color.

2. In the method of producing a multi-colored screen integral with the celluloid support the steps which consists in first sensitizing the celluloid support with a bichromated gelatine, photographing on said sensitized support configurations with the aid of a suitable matrix, washing out the gelatine not exposed to the light rays during the photographic process, tinting the remaining gelatine with a material not affecting the celluloid proper, and then subjecting the exposed celluloid to a tinting solution not affecting the gelatine.

In testimony whereof I affix my signature in the presence of two witnesses.

ISIDOR KITSEE.
